UNITED STATES PATENT OFFICE

169,916

COMBINED BED COVER SUPPORT AND HEALTH BOARD

Helen McLanahan Stevens, New York, N. Y.

Application July 8, 1952, Serial No. 20,509

Term of patent 14 years

(Cl. D5—2)

To all whom it may concern:

Be it known that I, Helen McLanahan Stevens, a citizen of the United States, residing in the city of New York, county of New York and State of New York, have invented a new, original, and ornamental Design for a Combined Bed Cover Support and Health Board, of which the following is a specification, reference being had to the accompanying drawing, forming a part hereof.

In the drawing:

Figure 1 is a perspective view of a combined bed cover support and health board showing my new design; and

I claim:

The ornamental design for a combined bed cover support and health board, as shown.

HELEN McLANAHAN STEVENS.
